John F. Neely,
By His Attorney,
James Dagger & Co.

UNITED STATES PATENT OFFICE.

JOHN FARLY NEELY, OF RENOVO, PENNSYLVANIA.

COMBINED DRAWER-PULL AND LABEL-CASE.

SPECIFICATION forming part of Letters Patent No. 372,559, dated November 1, 1887.

Application filed May 23, 1887. Serial No. 239,682. (No model.)

To all whom it may concern:

Be it known that I, JOHN FARLY NEELY, a citizen of the United States, and a resident of Renovo, in the county of Clinton and State 5 of Pennsylvania, have invented certain new and useful Improvements in Combined Drawer-Pulls and Label-Cases; and I do hereby declare that the following is a full, clear, and exact description of the invention, which will 10 enable others skilled in the art to which it app- pertains to make and use the same, reference being had to the accompanying drawings, which form a part of this specification, and in which—

Figure 1 is a perspective view of my com- 15 bined drawer-pull and label case, showing the lid of the case closed. Fig. 2 is a similar view showing the lid of the case open. Fig. 3 is a vertical sectional view taken on line $x-x$ of Fig. 1, and Fig. 4 is a detail view of the lid of the 20 case.

The same letters of reference indicate corresponding parts in all the figures.

My invention consists in a new and improved combined drawer-pull and label-case, which I 25 especially design for use in drug-stores, and which will be hereinafter fully described and claimed.

Referring to the several parts by letter, A indicates the outer end of a drawer of the usual 30 or ordinary construction, to which my improved combined drawer-pull and label-case is shown secured in its operative position.

B indicates the flat back of the pull, which is adapted to be secured to the outer end of the 35 drawer by the screws b , being formed with the perforations through which the said screws pass.

C C indicate the parallel side pieces of the draw-pull or label-case, which are secured at 40 their rear edges to the flat back B, and are connected at their front edges by the depending front D, which forms the pull proper, and beneath which the fingers are inserted in drawing out the drawer.

E indicates the flat bottom of the drawer, which is very narrow, and the front proper, F, of the case extends up slantingly from the for- 45 ward edge of the bottom E to the top of the depending pull B, as clearly shown in the sec- tional view, Fig. 3, of the drawings, thus leav-

ing room back of the pull B for the fingers in opening the drawer.

It will be seen that the depending front D forms a convenient pull for opening and closing the drawer, while the case formed by the 55 flat back B, the side pieces, C and C, and the bottom E and inclined front F forms a convenient receptacle for the reception of labels, or for a card containing the price of the goods in the drawer, and the top of this case is closed 60 by a hinged lid, H, which will be now described. This lid H, which is of a convenient size, is formed with the central open space, I, and with the longitudinal groove or recess J, ex- 65 tends from its rear edge to a point near its front edge, as shown in the sectional view, Fig. 3, of the drawings, and a glass label, M, marked with the name of the goods or articles contained in the drawer, is placed in the hinged lid by sliding it through the slot or recess J 70 from the rear edge of the lid until it is in position covering or filling the open central space of the lid, and this glass label is retained in position in the lid by means of the curved hinge-wires K K, these hinge-wires being 75 curved into nearly the form of a complete circle, leaving a suitable space between their ends, however, and these hinge-loops are first passed through apertures L L at the rear edge 80 of the lid H, and to the rear of the rear edge of the glass label M, when the latter is in position within the lid, and their rear ends are then passed back through apertures N N in the upper part of the flat back B of the pull or case before the said back has been screwed or fastened tightly against the front end of the drawer, and the screws which secured the said back to 85 the drawer are then tightened, so as to press the back B firmly against the drawer, and thus bind the inner ends of the hinge wires or 90 loops tightly between the drawer and the inner side of the back B, as will be readily under- stood, and as shown clearly in the sectional view, Fig. 3, of the drawings.

The hinged lid is held in its closed and in 95 its open positions by a spring, S, which is arranged, as shown in the drawings, so as to hold the lid firmly both in its closed and also in its open position.

My improved combined drawer-pull and 100

label-case is formed, preferably, of bronzed molding or metal bronzed, and is constructed of different sizes to suit the purchaser and the size of the drawer and of the labels.

5 From the foregoing description, taken in connection with the accompanying drawings, the construction and many advantages of my invention will be readily understood. It will be seen that it is simple and strong in construction and can be manufactured at a small cost, and that it is exceedingly convenient and efficient in operation, forming a convenient drawer-pull, and also a convenient case for labels, or for a card containing the prices of the articles contained in the drawer. The removable changeable glass label in the lid is also very convenient, showing at a glance the articles or particular medicine contained in the drawer, and this label can be readily removed 10 from the lid to be replaced by another when required, as when the contents of the drawer are changed, by merely unscrewing the flat back B from the drawer to free the inner ends of the hinge-loops, when the lid may be readily 15 removed from the case and the hinge-loops drawn out of their apertures in the rear of the lid to permit of the withdrawal of the glass label and the substitution of another, as desired.

Having thus described my invention, what I 20 claim, and desire to secure by Letters Patent of the United States, is—

1. The combined drawer-pull and label case consisting of the back adapted to be secured to a drawer, the side pieces, the narrow bottom and inclined front, and the depending 25 front piece, substantially as set forth.

2. The combination of the back adapted to be secured to a drawer, the side pieces, the narrow bottom and inclined front, the depending front piece, and the hinged lid, substantially as set forth. 40

3. The combination of the back adapted to be secured to a drawer, the side pieces, the narrow bottom and inclined front, the depending front piece, the hinged lid having the central opening and the longitudinal groove or slot, and the removable label adapted to fit in the said lid, substantially as set forth. 45

4. The combination, in a drawer-pull and label-case, of the flat back adapted to be secured to a drawer and having the apertures formed in it near its upper edge, the parallel side pieces, the narrow bottom and inclined front, the depending front piece, the lid formed with the central opening, the longitudinal recess or slot and the transverse apertures at its rear edge, the removable label adapted to fit in the said lid, and the hinge loops or wires, all substantially as and for the purpose herein set forth. 50

5. The combination of the back adapted to be secured to a drawer, the side pieces, the narrow bottom and inclined front, the depending front piece, the hinged lid, and the spring, substantially as set forth. 55

In testimony that I claim the foregoing as my own I have hereunto affixed my signature in presence of two witnesses.

JOHN FARLY NEELY.

Witnesses:

C. R. COLLINS,
W. P. MAXWELL.
